UNITED STATES PATENT OFFICE.

BERNARDO ALBERGOLI, OF LAS ROSAS, ARGENTINA.

SEPARABLE CHAIR.

1,392,242.

Specification of Letters Patent. Patented Sept. 27, 1921.

Application filed March 22, 1920. Serial No. 367,976.

To all whom it may concern:

Be it known that I, BERNARDO ALBERGOLI, a citizen of the Argentine Republic, residing at Las Rosas, Province of Santa Fé, 5 Argentine Republic, have invented new and useful Improvements in Separable Chairs, of which the following is a specification.

This invention relates to chairs and more particularly to the type of chairs in which 10 the construction permits of the chairs being readily assembled and disassembled, whereby the chairs may be shipped from place to place in "knock-down" fashion.

A feature of this invention is the arrangement and construction of parts whereby a 15 "knock-down" chair may be easily assembled without the aid of special tools and whereby the component parts of the chair, when assembled, are rigidly and firmly held 20 in the desired relation to each other.

A further feature of this invention is the provision of a "knock-down" chair in which all the parts, including the seat, are formed 25 of relatively narrow strips. This has the advantage of permitting the chair to be manufactured from material of narrow width which otherwise could not be used in chair construction and which is less expensive than wide material.

30 Generally considered, the chair of this invention comprises a seat portion; front legs secured to the seat portion, each by a relatively short bolt; rear legs and a separate and independent back portion secured to 35 each other and to the seat portion by a pair of bolts, one at each side of the chair, and each having an end anchored in the back portion, the other end anchored in the rear leg, and an intermediate portion passing 40 through an aperture provided in the seat portion for the purpose; and a plurality of relatively narrow slats adapted to be assembled upon the seat portion to constitute the seat proper.

45 In the accompanying drawings:

Figure 1 is a sectional side elevation of the chair of the present invention taken through the center of the chair.

Fig. 2 is a sectional side view of a portion of the chair showing particularly the manner in which the front and rear legs and the back-rest of the chair are secured together.

Fig. 3 is a top plan view of the seat portion of the chair, the slats constituting the

seat proper being assembled for use and the back rest members being shown in section.

Fig. 4 is a similar plan view, but showing merely the seat portion without the seat slats.

Fig. 5 is a sectional view taken on the line *a-a* of Fig. 4.

Fig. 6 is a sectional view taken on the line *b-b* of Fig. 3.

Referring to the drawings, the seat portion, which forms the basic element of the chair, is constituted by side bars 1 and 3, rear bar 2 and a front bar 5, firmly secured together by any suitable means to form a rectangular framework. On the inside 65 edges of the side members 1 and 3 there is formed grooves 4 into which the ends of a plurality of slats 9 are adapted to be lodged, edge to edge, to form the seat proper. The top of the front member 5 is slightly below 70 the level of the grooves 4 so that the slats 9 can be slid with ease into and along the grooves 4. After all the slats are assembled they are maintained in place and the level 75 of the front member is raised to the level of 80 the side members by a bar 6 which is secured to the front bar 5 by screws 7 passing through holes 8 in the member 5. Another function of the bar 6 will be described hereinafter. The front and rear members also 85 have grooves for the reception of the sides of the end slat and therefore further hold the slats in place.

Each of the front legs 15 is secured to the seat portion of the chair by a bolt 13 passing 90 through holes provided in the seat portion and the leg 15. The bolt 13 extends parallel with the leg of the chair and in one sense forms a continuation thereof. The head of the bolt is uppermost and contacts with the 95 top of the front member 5. The other end of the bolt is threaded as usual and adjacent this threaded portion a suitable opening is provided in the leg for the reception of a nut 14 which bears against the sides of the 100 opening when the bolt is tightened and thus holds the bolt firmly and securely to the leg, and through the head of the bolt holds the seat portion of the chair to the leg. In assembling the nut it is first placed in the 105 opening and then the bolt is turned until the threaded portion thereof passes through the nut and the parts securely held. After the leg is assembled, the opening is closed by a suitable plug to conceal it. The bar 6 for 110

the front member 5 is cut out to receive the head of the bolt, and therefore when the bolt is tightened and the bar 6 put in place the head of the bolt 13 will be concealed.

5 The rear legs 19 and the back-rest members 17 are independent and separate, but the leg and back-rest member of each side are connected together and to the seat portion of the chair by a screw-threaded rod 16. 10 This rod 16 passes through holes in the leg and back member and through a hole 18 in the seat portion of the seat and is provided at its ends with screw-threaded portions which receive nuts 20 and 21 mounted 15 in openings 22 and 23 in the leg 19 and back member 17 respectively, the openings 22 and 23 being similar to the openings in the front legs above described and being likewise subsequently filled with plugs. When the nuts 20 are tightened the rod 16 will securely hold 20 the back member 17 and the leg 19 to the seat portion of the chair. The rod 16 does not extend for any great length but terminates relatively close to the seat portion 25 where it is provided with the nuts 20 and 21.

25 The seat slats 9 may be further supported against sagging by a slat 10 which extends transversely of the slats 9 and which is lodged in a slot 11 in the rear member 2 and 30 a slot 12 in the front member 5.

30 It will be readily understood by those skilled in the art that the chair above described can be cheaply and economically manufactured and easily assembled and disassembled.

35 I claim as my invention:

1. A demountable chair comprising in combination, a seat frame the side members

of which are formed with grooves and the front member of which has its top slightly 40 below the level of said grooves, a bar fitting on the top of said front member and having its upper face flush with the upper level of the side members, front legs each made in a single piece, a relatively short bolt securing each front leg to the seat frame, each bolt extending vertically through and having its head in engagement with the front member of the frame, said bolt also extending vertically into the upper end portion 45 of the leg and having its screw-threaded end in engagement with a nut located in an opening in said leg, a seat comprising slats arranged transversely of said seat frame and having their ends located in said grooves, 50 said bar covering the heads of said bolts and maintaining said slats against removal, and rear legs and a back rest secured to said seat frame.

2. A demountable chair comprising a seat portion; front legs; a relatively short bolt having its head in engagement with a cross member of the seat portion and its nut lodged in an opening in the leg for securing each leg to the seat portion; a seat comprising a plurality of narrow slats adapted to be slid into the seat portion and held thereto by grooves in the side members of the seat portion, the grooves being open at the front of the seat portion; and a front cross piece 65 70 adapted to cover the bolt heads and at the same time to lock the slats in position in the grooves substantially as described.

In testimony whereof I have signed my name to this specification.

BERNARDO ALBERGOLI.
